UNITED STATES PATENT OFFICE.

EARL D. BROWN, OF TOLEDO, OHIO.

BREAST PUMP.

Application filed April 27, 1922. Serial No. 556,836.

To all whom it may concern:

Be it known that I, EARL D. BROWN, a citizen of the United States, and a resident of Toledo, in the county of Lucas and State 5 of Ohio, have made an Invention Appertaining to a Breast Pump; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates primarily to a breast pump of the type having a plunger and cylinder connected therewith and operable to create suction within the breast piece of the instrument.

20 The object of the invention is the provision of a simple and efficient instrument of the class described which is easily operable with one hand and embodies a novel arrangement and assembly of its parts to facilitate cleaning and substitution of the 25 parts.

The invention is fully described in the following specification, and while, in its broader aspect, it is capable of embodiment 30 in numerous forms, a preferred embodiment thereof is illustrated in the accompanying drawings, in which,

Figure 1 is a central longitudinal section of a breast pump embodying the invention 35 with parts in full, and Fig. 2 is a cross-section thereof on the line 2—2 in Fig. 1.

Referring to the drawings, 1 designates a body member of circular form in cross section and having a passage 2 axially there- 40 through, with one end enlarged to form a valve chamber 3 and its other end provided with an interiorly threaded enlargement 4.

The cylinder of the pump is formed by a tubular member 5 threaded at its inner 45 end on the end of the member 1 in which the valve chamber 3 is disposed and having its opposite or outer end closed by a cap 6, which is removably threaded thereon. A piston 7 is mounted in the cylinder 5 for 50 reciprocatory movements therein and has its stem 8 extending toward the cap 6 and provided with an axial socket 9 for receiving a guide stem 10 projecting into the cylinder axially thereof from the closed end of the 55 cap 6. The stem 8 is formed with the cross-bar 11, which projects at its ends through

longitudinally extending slots 12 in the cylinder 5 to form finger engaging parts without the cylinder. A coiled expansion spring 13 encircles the stems 8 and 10 between the cross-bar 11 and cap 6 and normally tends to hold the piston at the limit of its forward stroke. The pump is easily operated by one hand by placing the thumb against the outer end of the cap 6 and the first and second fingers in straddling relation to the cylinder and in pulling engagement with the ends of the cross-bar.

A disk valve 14 is mounted in the valve chamber 3, being retained therein for limited movements by a plug 15 threaded in the outer end of said chamber and apertured or notched to permit the passage of air from the valve chamber into the cylinder, the valve being intended to open during an outward or suction stroke of the piston 7 and to close during an inward stroke of the piston. The piston is provided therethrough with a passage 16, which opens communication between the cylinder at the inner and outer sides of the piston and is provided with an enlargement for receiving a disk valve 17, which seats to close the passage under an outward or suction stroke of the piston and opens during an inward stroke of the piston. The valve is retained in the chamber by a plug 18, which is apertured or slotted to permit the passage of air therethrough.

A breast cup 19 of bell form and preferably of glass is secured at its inner end to the outer end of the body member 1 by a screw 20, which extends through a restricted opening in the inner end of the breast cup and threads into the enlargement 4 of the body member. A washer 21 of rubber or other yielding material is disposed between the adjacent ends of the body 1 and breast cup to provide a close joint therebetween when the screw 20 is tightened. Said screw has a passage longitudinally therethrough to open communication between the interior of the breast cup and the passage 2. The breast cup is provided in the under side thereof with the customary liquid receiving bowl 22.

23 designates a petcock or relief valve which is threaded into the body member 1 in communication with the passage 2 to relieve the vacuum in the breast cup 19 when desired.

It is evident that the breast cup and cylin-

der 3 form a rigid structure and are detachably connected in a manner to facilitate an easy and quick separation thereof for the purpose of cleaning, sterilizing or 5 substitution and that the power or suction stroke of the piston is imparted thereto by a closing action of the hand grasping the instrument, the spring serving to return the piston to the forward end of its stroke to 10 exhaust the air from the cylinder through the valve passage 16 and the cylinder slots 12.

I wish it understood that my invention is not limited to any specific construction, arrangement or form of the parts as it is capable of embodiment in numerous forms 15 without departing from the spirit of the claims.

Having thus described my invention, what I claim as new, and desire to secure by Letters Patent, is,—

1. In a breast pump, a body having an axial passage with its inner end enlarged to form a valve chamber, and its outer end internally threaded, a slotted cylinder secured 25 at its inner end to the inner end of the body, a cap secured to and closing the outer end of the cylinder, a reciprocal piston in the cylinder having a stem provided with an axial socket, a guide stem secured to the closed end 30 of the cap and slidably received in the socket of the piston stem, operating means for the piston connected to the stem thereof, and

extending through said cylinder slots, a coil spring encircling the piston and guide stems and abutting the closed end of the cap at 35 one end and the operating means for the piston at its opposite end, a valve in said valve chamber of the body, a valve controlled passage in the piston, a breast cup, and a screw having an axial passage extending 40 through the closed end of the breast cup and threaded into engagement with the said interior threads at the outer end of the body and having a head engaged against said closed end of the breast cup. 45

2. In a breast pump, a body, a slotted cylinder rigidly connected at one end to one end of the body and having a closed outer end, a breast cup rigidly connected to the opposite end of the body, a piston in the body having a stem formed with an axial socket and disposed between the cylinder ends, operating means on the stem extending through the cylinder slots, a guide stem rigidly affixed to the closed end of the cylinder and slidably received in the socket of the piston stem, a coil spring encircling the stems and abutting the closed cylinder end and the operating means on the piston stem, and valve controlled passages in the body 50 and piston. 55

In testimony whereof, I have hereunto signed my name to this specification.

EARL D. BROWN.
